FOURDRINIER PAPER MAKING MACHINE

Bernard A. Malkin, Lachine, Quebec, Canada,
assignor to Dominion Engineering Works Limited,
Lachine, Quebec, Canada

Application March 22, 1934, Serial No. 716,866

13 Claims. (Cl. 92—44)

This invention relates to Fourdrinier paper making machines of the type in which the table roll section is shifted laterally to facilitate replacement of the forming wire and has, as its principal object, the provision of simple and practical means for supporting the table roll section so that the desired lateral displacement may be accomplished in a more convenient and advantageous manner as compared with present practice.

Another object is the provision of a generally improved construction in which supporting beams or rail members are arranged to travel with the table roll section and to support one side thereof on the cantilever principle during movement of the table roll to and from operative position.

Other objects, advantages and characteristic features of the invention will be more readily understood from the following detailed description taken in connection with the accompanying drawings.

Fig. 1 is an end view of a Fourdrinier table roll section and mounting means designed in accordance with this invention. In this view the table roll section is shown in its normal or operative position.

Fig. 2 is a view similar to Fig. 1 but showing the table roll section in a position intermediate its operative and fully displaced positions.

Fig. 3 is a view similar to Fig. 1 but showing the table roll section in its fully displaced position.

Figs. 4, 5 and 6 are views corresponding respectively with Figs. 1, 2 and 3 but showing certain modifications.

Fig. 7 is a side elevation of the table roll section as it appears in its fully displaced position when looking toward the side adjacent the pit.

Figs. 8, 9 and 10 are views corresponding respectively to Figs. 1, 2 and 3 but showing still further modifications.

Fig. 11 is a view, similar to Fig. 7, but specific to the modification shown in Figs. 8, 9 and 10.

A simple embodiment of the invention applied to the table roll section of a Fourdrinier machine is shown in Figs. 1, 2 and 3 in which, for the sake of clearness, other portions of the paper making machine are omitted. As here shown the table roll section 5 includes a series of transverse beam or rail members 6, only one of which appears in the drawings. Each beam or rail member projects beyond the sides of the main portion of the table roll section and is provided with a laterally projecting bottom flange 7. As shown in Fig. 1 the table roll section is normally

centered over the usual pit 8 with the flanged bottom portions of the beams or rail members 6 resting on two series of supporting rollers indicated at 9 and 10. These rollers are carried by two series of roller stands 11 and 12 located in 5 the aisles 13 and 14 near opposite sides of the pit.

Additional roller stands 15 and 15a are arranged in the aisle 13 so that the rollers 16 thereof cooperate with the rollers 9 to provide supports on which the beam or rail members 6 10 rest when the table roll section is in the laterally displaced position shown in Fig. 3. Further roller stands 17 are also located in the aisle 13 between the previously mentioned stands 11 and 15a. These roller stands 17 project above the remaining stands and carry rollers 18 positioned to engage the upper surfaces of the beam or rail flanges 7, as indicated in Figs. 2 and 3.

When the forming wire (not shown) is to be replaced the table roll section 5 is shifted to the 20 left from the position shown in Fig. 1 to the position shown in Fig. 3. During the initial part of this movement the rails or beams 6 travel on and are supported solely by the rollers of the stands 11 and 12, located at opposite sides of the pit. As 25 the table roll section continues its movement to the left the leading ends of the beam or rail flanges 7 engage beneath the rollers of the stands 17 just before the trailing ends of the beam or rail members 6 leave the supporting rollers of 30 the stands 12. As the beams or rails 6 pass entirely out of engagement with the rolls of the stands 12 the beams or rails 6, in conjunction with the rollers of the stands 11 and 17, support the table on the cantilever principle until the 35 table reaches a balanced position on the supporting rollers located in the aisle 13.

During return movement of the table the beam or rail flanges 7 do not pass out of engagement with the rollers of the stands 11 until shortly 40 after the leading ends of the rails or beams are advanced to a position resting on the rolls 10 of the stand 11. It will thus be seen that the beams or rails 6 cooperate with the rollers of the stands 11 and 17 to maintain the table in a 45 horizontal position during the unbalanced part of its travel to or from an operative position.

The table roll section 5 may be simply pushed to and from its operative position or the rolls 9 may be power driven and provided with pinion 50 teeth meshing with racks formed on or fixed to the undersides of the engaging beams or rails 6.

In the modification shown in Figures 4 to 7 inclusive the same result is accomplished by the use of auxiliary beams or rail members 20 coop- 55

erating with the main beams or rails 6 of the table roll section. These auxiliary members 20 are mounted to slide on rollers 21 and 22 (Fig. 4) carried by roller stands 23 and 24 located in the aisle 14. Additional roller stands 25, located between the stands 23 and 24, carry rollers 26 which bear on the upper surfaces of the members 20. The table roll section 5 and the auxiliary beam or rail members 20 are relatively arranged as shown in Fig. 4 when the table roll section occupies its normal operative position over the pit 8. As here shown the main beam or rail members 6 rest on rollers 27 and 28, the rollers 27 being carried by the auxiliary beams 20 and the rollers 28 being carried by roller stands 29 located in the aisle 13 close to the adjacent side of the pit. Additional roller stands 30, arranged in the aisle 13, carry rollers 31 which cooperate with the rollers 28 to support the table roll section 5 when the latter is in its fully displaced position shown in Fig. 6.

When the table roll section is positioned as shown in Fig. 4 the auxiliary beams 20 are detachably fastened to the main beams 6 to travel therewith when the table roll section is shifted to the left from the position shown in Fig. 4 to that shown in Fig. 5. In the present instance each beam 6 (of which there are 2 as shown in Fig. 7) is provided with a latch in the form of a bell crank lever 32 fixed to rotate with a rock shaft 33 and having one arm 34 provided with a hooked terminal 35 adapted to engage behind a projection 36 on the associated auxiliary beam 20. The remaining arm 37 of one of the latches 32 is connected by a rod 38 to a latch releasing lever 39 that is pivoted to the associated beam 6. A spring 40 encircles the rod 38 between suitable abutments 41 and 42 and normally tends to urge the latches 32 to the operative position shown in Fig. 4.

From the drawings and the foregoing description it will be apparent that the auxiliary beams 20 cooperate with the associated rollers 21 and 26 to serve as cantilever supports for the trailing side of the table roll section as the latter is shifted to the position shown in Fig. 5. When the table roll section reaches this position it is balanced on the supporting rolls 28 and certain of the rolls 31 located in the aisle 13 so that the auxiliary beams 20 may be then released (by operating the levers 39 to pull the latch arms 37 back against suitable stops 37a) and withdrawn to their original position as shown in Fig. 6, the movement of the table roll section to the left being then continued until it reaches its final displaced position also shown in Fig. 6.

In returning the table roll section to its operative position it is first shifted to the right from the position shown in Fig. 6 to that shown in Fig. 5. The auxiliary beams 20 are then shifted to the left from the position shown in Fig. 6 to that shown in Fig. 5 so that the projections 36 thereof are engaged beneath the latch members 32. The movement of the table roll section to the right may then be continued since the advancing end of the table roll section is now adequately supported by the auxiliary beams as it travels back to its final operative position shown in Fig. 4.

In order to facilitate the aforesaid movements of the table roll sections the supporting rolls 28 thereof are driven by a power shaft 44 through suitable enclosed gearing generally indicated at 45. While not shown in the drawings these roll-

ers 28 may be provided with pinion teeth meshing with racks at the undersides of the main beams or rails 6.

Each of the auxiliary beams 20 carries angle plates 47 and 48. The plate 47, as shown in Fig. 4, is bolted to the standard 25 to temporarily hold the beam 20 against accidental movement when the table roll section is in use. Similarly the plate 48 is adapted to be bolted to the standard 25 to hold the beam 20 in the position shown in Fig. 5 in cases where the beams 20 are shifted to this position prior to return movement of the table roll section from the position shown in Fig. 6 to that shown in Fig. 5.

In the further modification shown in Figs. 8 to 11 inclusive an auxiliary beam 51 is slidably arranged in each of the hollow transverse beams 52 of the table roll section 5. At its inner end each beam 51 is provided with upper and lower bearing rollers 53 riding the top and bottom members of the enclosing beam 52, the inner end of which is similarly equipped with upper and lower rollers 54 riding the top and bottom portions of the beam 51. In this case the table roll section is normally supported over the pit 8 as shown in Fig. 8. As here indicated the outer ends of the auxiliary beams 51 rest on and are releasably secured to suitable stands 55 located on the rear baseplate while the outer ends of the main beams 52 rest on supporting rollers 56 carried by roller stands 57 located in the aisle 13. The means for fastening the outer end of each auxiliary beam 51 to its supporting stand 55 may take any form that will permit the beam to be readily released from the stand. In the present instance each beam 51 is provided with an angle plate 57a adapted to be bolted to the stand as indicated at 58 in Figs. 8 and 9.

During movement of the table roll section from the operative position shown in Fig. 8 to the fully displaced position shown in Fig. 10 the auxiliary beams 51 cooperate with the main beams 6 and the stands 55 to serve as cantilever supports for the trailing side of the table roll section until the latter reaches a balanced position on the supporting rollers 56 and 60 located in the aisle 13 as shown in Fig. 9, the rollers 60 together with certain additional rollers 61 being respectively carried by suitable stands 62 and 63. After the table roll section reaches its balanced position on the rollers 56 and 60 the auxiliary beams 51 may be released from the stands 55 and shoved into the beams 52 and the movement of the table roll section to the left continued until it rests on the three sets of rollers 56, 60 and 61 as shown in Fig. 9.

In returning the table roll section to its operative position it is first shifted to the right from the position shown in Fig. 10 to a balanced position similar to that shown in Fig. 9. The auxiliary beams 51 are then withdrawn from the beams 52 and fastened to the stands 55 to support the advancing side of the table roll section during the remainder of its travel to the operative position shown in Fig. 8.

Having thus described my invention, what I claim is:-

1. A Fourdrinier paper machine equipped with a laterally movable table structure, rollers mounted independently of the table and arranged to support the table in either an operative or a laterally displaced position and further rollers beneath which portions of the movable table structure are engaged to prevent tilting of the

- table during its lateral movement to and from an operative position.
2. A Fourdrinier paper machine equipped with a laterally movable table including transverse rail members, rollers on which said rail members travel during lateral movement of the table to or from an operative position and further rollers beneath which the rail members are engaged to prevent tilting of the table during its lateral movement, all of said rollers being mounted independently of the table and rail members.
3. A Fourdrinier paper machine equipped with a laterally movable table, rollers mounted independently of the table and arranged to support the table in either an operative or a laterally displaced position, means for driving certain of said rollers to propel the table to or from either of said positions and further rollers beneath which portions of the table are engaged to prevent tilting of the table during its lateral movement to and from an operative position.
4. A Fourdrinier machine as claimed in claim 2, in which each rail member comprises two separately connected sections, one section being arranged to travel on supporting rollers located in the aisle at one side of the machine and the other section being arranged to travel between upper and lower rollers located at the opposite side of the machine.
5. A Fourdrinier paper machine equipped with a laterally movable table, extension members adapted to be detachably secured to said table to form lateral extensions movable therewith, independently mounted rollers arranged to support the undersides of the table and extension members during lateral movement thereof, and further rollers arranged to bear on the upper surfaces of said extension members.
6. A Fourdrinier machine as claimed in claim 5 including means for driving certain of said rollers to furnish power for effecting lateral movement of said table and extension members.
7. A Fourdrinier machine including a laterally movable table equipped with laterally projecting extensions movable therewith, rollers mounted independently of the table and arranged to support the table in either an operative or an inoperative position, means for driving certain of said rollers to propel the table to or from either of said positions, said driven rollers being in direct, uninterrupted, propelling engagement with the table in all positions of the latter, and means arranged to bear on the upper surfaces of said extensions to prevent tilting of the table when it reaches an unbalanced position during its lateral movement in either direction.
8. A Fourdrinier paper machine equipped with a laterally movable table including fixed transverse rail members, extension rails adapted to be detachably connected to said fixed rail members to form continuations thereof at one side of the table, independently mounted rollers arranged to support the underside of said fixed transverse rail members during lateral movement thereof, sim-

ilar independently mounted rollers arranged to support the undersides of said extension rails during lateral movement thereof, and additional rollers bearing on the upper surfaces of said extension rails to prevent tilting thereof when the table reaches an unbalanced position during its lateral movement in either direction. 5

9. A Fourdrinier paper machine equipped with a laterally movable table including transverse rail members permanently fixed to move therewith, auxiliary rails slidably mounted at one side of said machine between upper and lower supporting and guiding members bearing respectively against the upper and lower surfaces of said auxiliary rails, said auxiliary rails being disposed to 15 extend beneath adjacent ends of said fixed rails to support one side of the table when the latter is in its operative position.

10. A Fourdrinier paper machine equipped with a laterally movable table including transverse rail members movable therewith, independently mounted supporting elements on which said rail members travel during lateral movement of the table to or from an operative position and independently slidably auxiliary rail members cooper- 25 able with the first mentioned rail members and with further independently mounted rail supporting elements to support one side of the table until the latter reaches a balanced position during its lateral movement in either direction. 30

11. A Fourdrinier paper machine equipped with a laterally movable table including transversely extending rails of telescopic construction, each rail comprising a main section fixed to travel with the table and an auxiliary section slidably 35 associated with the main section, independently mounted supports at one side of the table to which the outer ends of the auxiliary rail sections are secured and other supports at the other side of the table on which the fixed rail sections travel 40 during lateral movement of the table to or from an operative position.

12. A Fourdrinier paper making machine equipped with a laterally movable table, including transversely extending rails of telescopic construction, each rail comprising a hollow section fixed to travel with the table and an auxiliary section slidably mounted within the hollow section, supports at one side of the table to which the outer ends of the auxiliary rail sections are 45 secured and supports at the opposite side of the table on which the hollow rail sections travel during lateral movement of the table to or from an operative position.

13. A paper making machine as claimed in 55 claim 12 including upper and lower rollers on the inner end of the auxiliary section bearing respectively against upper and lower portions of the hollow section and upper and lower rollers carried by the hollow section and bearing re- 60 spectively on the upper and lower surfaces of the inner section.

BERNARD A. MALKIN.
